UNITED STATES PATENT OFFICE

2,192,890

ELECTRIC CURLING IRON

Joseph Boda, Budapest, Hungary

Application November 20, 1937, Serial No. 175,606
In Switzerland June 2, 1937

4 Claims. (Cl. 219—24)

My invention relates to improvements in electric curling irons in which the stationary arm operates in conjunction with the oscillating arm of the scissor-like device; and the objects of my improvement are, first, to provide a continuous and instantaneously controllable heating of both arms; second, to afford facilities for the proper adjustment of both oscillating frequency and turning moment of the said arm; and, third, to provide means rendering the switching-on and switching-off of the motor adjustable and, after this adjustment, however, automatic.

The straight human hair possesses a circular cross-section, and the curly hair a flat oval one. Between these two forms there is a great number of intermediate forms, i. e., the more or less wavy hair. In order, therefore, to put waves or curls into the hair, it becomes necessary to change the cross-sectional shape of the hair, i. e., the hair which is too circular must be pressed into an oval form. This may be accomplished by the application of pressure, heat and moisture. It is obvious that all these measures may be applied at one and the same time or successively. The application of pressure upon the hair, however, is indispensable. Additional heating in connection with moisture substantially facilitates the work, i. e., less pressure and less time than is required for attaining the same final result. Working with pressure and heat simultaneously requires less effort and allows one to do the work quicker. The flattening of the hair also may be speeded up by using softeners, i. e., aqueous alkaline solutions, when laying the curls.

Of late yet another process has been made known in which the cross-section of the hair is mechanically flattened or rolled out by means of a curling iron in which one leg oscillates rapidly to and fro. The oscillations of this leg take place with a relatively high frequency so that the hair is treated 200 to 6000 times per minute. The operation is similar to that used in bending metal parts, wherein a strip of sheet iron, for example, is drawn through a device comprising a bottom part in the form of a stationary groove or mould and a top part in the form of a roll revolving to and fro about its axis. According to the amount of pressure exerted by the roll on the strip and according to the speed with which the latter is drawn through the device a more or less pronounced curvature is imparted to the strip. Using in place of the roller device a similarly built curling iron and drawing a pencil of hair under pressure through the iron the hair is flattened

out and, at the same time, waved. The skill of the hair dresser then brings about the desired wave or curl in the hair.

This process alone, however, has not yielded the desired result, since an equal waving of the hair could not be obtained.

The present invention relates to a curling iron with which one is able, by means of the proper mechanical and heat treatment, to obtain absolutely equal waves in a very short time.

In order to render it possible to switch off the motor revolving at an increasing speed and to switch it on with the full turning moment when revolving at a decreasing speed, an adjustable centrifugal control is built into the curling iron which, in connection with a switch, renders the switching on and off of the motor adjustable and after this adjustment, however, automatic.

If, now, we select a lower frequency the voltage of the motor circuit is, furthermore, so changed that the motor starts with an increased torque. The devices for controlling the frequency of the oscillations and those for adjusting the degree of heating, finally, are mounted in places easy of access so that the varying conditions when working with the curling iron at any time may be taken into account.

The present curling iron also is especially adapted to the fact that the human hair, both as to thickness and strength, varies in wide limits. For this reason all the operative functions also are adjustable, i. e., the degree of heating, the frequency of the movable leg and the pressure upon the legs. The frequency and heating are mechanically adjustable, while the pressure upon the legs of the curling iron is adjustable in wide limits by the highly sensitive hand of the operator.

The above-mentioned objects are attained by the apparatus shown, by way of an example, in the accompanying drawing, in which—

Fig. 1 is a longitudinal section through the curling iron;

Fig. 2, a cross-section through the latter.

1 In Fig. 1 refers to the roll-leg of the curling iron, 2 to the heating element of the said leg, 3 to the trough-shaped second leg of the iron with its heating element 4. The drive for the oscillating leg 1 is inside the housing 5. The two handles 6 and 7 turn about the pin 8. A flexible shaft 45 is contained within the handle 7 and the metal hose 9. The said shaft transmits the revolutions of the motor shaft 17 upon the drive of the leg 1. In the housing 16 there is the rotor 10 and the stator 11 of the motor running in the bearings 12. 55

- A controllable resistance 13 serves for the purpose of adjusting the degree of heating of the two legs of the curling iron, and this adjustment is effected by means of the contact 14 and the setting knob 15.
- The adjustment of the frequency of oscillation of the leg 1 is accomplished by means of a centrifugal switch which opens a contact lying in the motor circuit at higher speeds of revolution.
- 16 The contact 18 of this latter device is stationary. When the motor is not running the motor circuit is closed by means of a spring 23. When the motor is running the weights 20 of the centrifugal control move away from each other, the movable contact 19 moves away from the said stationary contact 18 and interrupts the motor circuit until the number of revolutions of the motor per minute has decreased to such a point that the two contacts 18 and 19 again approach and contact each other due to the drop of the centrifugal force and due to the tension of the said spring 23. The speed of the motor may be adjusted from the outside by means of the spindle 21 and the screw 22. The latter also may serve, e. g., to so change the resistance in the motor circuit that the motor is given a higher torque at a low number of revolutions.

What I claim and desire to secure by Letters Patent is:

- 20 1. An electric vibrating curling iron of the character described, comprising, in combination, a vibrating and a stationary leg pivoted to each other in scissor-like fashion, electrical heating

elements for each of said legs, an adjustable electrical resistance for controlling the heating of the said elements, a flexible shaft in the handle of the said vibrating leg, an eccentric drive for said vibrating leg and disposed in said leg, an electric motor for operating the said shaft, and a centrifugal control for adjusting the frequency of vibration of the vibrating leg; and means for regulating the turning moment of the vibrating leg at low vibration frequencies.

2. An electrically operated vibrating curling iron according to claim 1, wherein said regulating means includes a resistance in the motor circuit, means for adjusting the said resistance, and means co-operating with the last-mentioned 15 means for adjusting the speed of the motor; the whole in such a combination that the voltage of the motor circuit is so changed in the course of an adjustment to a lower motor speed that the torque of the motor is increased.

20 3. An electrically operated vibrating curling iron according to claim 1, including a contact in combination with the said adjustable centrifugal control for the purpose of switching off the motor in the case of an increasing speed of the 25 latter and of again switching it on with the full turning moment in the case of a decreasing speed.

4. An electrically operated vibrating curling iron according to claim 1 wherein the control devices for adjusting the degree of heating and for adjusting the number of vibrations are mounted in the cap of the motor.

JOSEPH BODA.
